Application January 21, 1942, Serial No. 105,348

Term of patent 14 years

To all whom it may concern:

Be it known that we, John F. Dauster, Ralph E. Hartline, and Paul C. Perrin, citizens of the United States, residing respectively at Wilkinsburg, Swissvale, and Pittsburgh, in the county of Allegheny and State of Pennsylvania, have invented a new, original, and ornamental Design for a Gas Detector, of which the following is a specification, reference being had to the accompanying drawing forming a part thereof.

Fig. 1 is a top plan view of a gas detector embodying our new design;

Fig. 2 is a side elevational view thereof;
Fig. 3 is a front view thereof;
Fig. 4 is a rear elevational view thereof; and
Fig. 5 is a bottom plan view thereof.

We claim:

The ornamental design for a gas detector, substantially as shown.

JOHN F. DAUSTER.
RALPH E. HARTLINE.
